UNITED STATES PATENT OFFICE.

EUGENE WIET, OF SAN FRANCISCO, CALIFORNIA, ASSIGNOR TO PARROTT & COMPANY, OF SAN FRANCISCO, CALIFORNIA, A CORPORATION OF CALIFORNIA.

MACHINE FOR MANUFACTURING STEEL STUDDING.

1,141,595.

Specification of Letters Patent.

Patented June 1, 1915.

Application filed October 30, 1912. Serial No. 728,680.

To all whom it may concern:

Be it known that I, EUGENE WIET, a citizen of the United States, and a resident of the city and county of San Francisco, State 5 of California, have invented new and useful Improvements in Machines for Manufacturing Steel Studding, of which the following is a specification.

The objects of the invention are to com-

10 combine in one machine coördinated, synchronized, coöperative mechanisms adapted to automatically or semiautomaticaly produce finished interlocking steel studding or the like from the raw material.

15 Another object is to produce a novel feeding mechanism adapted to feed parallel strips of material at perfectly registered speed throughout their travel.

20 A further object is to so arrange the combination of functional elements in the machine and so coördinate their action and adjustment that a wide range of products and sizes of products may be produced by the machine.

25 The invention possesses other advantageous features which with the foregoing will be set forth at length in the following description, where I shall outline in full that form of invention selected for illustration 30 in the drawings accompanying and forming part of the present specification.

35 The novelty of the invention will be included in the claims succeeding said description. From this, it will be apparent that I do not restrict myself to the showing made by said drawings and description, as I may adopt many variations within the scope of my invention as expressed in said claims.

40 This machine is designed primarily to produce what is known in the trade as "Collins interlocking steel studding and suspended ceiling construction," and is illustrated and will be described in the production of this particular type of structure. I do not wish, 45 however, to be confined to this specific type of product in the interpretation of the scope of my invention.

50 The novel combination of elements of this machine with certain modifications in the structure or operation would lend itself to the production of other like products without departing from the spirit of this invention as defined in the claims.

First notching and feeding the strips as hereinafter described is the dominating element in the operation of this machine; the succeeding actions may be performed manually or in various ways.

55 In the drawings: Figures 1, 2 and 3 should be read from right to left to give a connected diagramic elevation of a machine constructed in accordance with this invention. Fig. 1 is a side elevation of the notching press and the feeding mechanism. Fig. 2 is a side elevation of the cutting off 60 press, the channeling or flanging press and the tie clip placer. Fig. 3 is a side elevation of the tie clip clenching press and the ejector. Fig. 4 is a detail side elevation of the notching die. Fig. 5 is a detail plan 65 view from above of the same, partially broken away to disclose the die plate. Fig. 6 is a detail side elevation of the cutting off dies and supporting guides. Fig. 7 is an end elevation of the same. Fig. 8 is a detail side 70 elevation of the synchronizing tripping mechanism of the cutting off press. Fig. 9 is an end elevation of the machine in front of the channeling dies at IX—IX. Fig. 10 is a fragmentary perspective view of a section 75 of studding installed for a wall. Fig. 11 is a fragmentary detail showing the tie clip assembled across the channel strips. Fig. 12 is a detail in side elevation of the tie clip feeding mechanism.

80 In detail the construction consists of the reel base 1 having the rollers 2, upon which the reels of band steel 3 are supported. The ends of the band steel hereinafter called the strips 5 are passed under the spring mounted 85 rollers 6 which exert sufficient pressure to prevent the strips from backing up, or rising from the runways between these rollers.

85 The ends of the strips are passed between the punches 7 and dies 8 that are mounted on the carrier 9. The notching press A is started by throwing over to the right the starting lever 11 that is linked to the clutch mechanism 12 splined upon the main drive shaft 13 that is rotated by the loose pulley 14 belted to the prime mover (not shown). The rotation of the drive shaft acting through the bevel pinion 15 rotates the bevel gear 16 having the adjustable crank pin 17 fixed therein. This pin reciprocates in the slot 18 in the sector 19 that is pivoted at 20

to the foundation 21 of the machine. The rack segment 22 fixed upon the sector is enmeshed with the pinion 23 formed upon the gear 24. This gear is enmeshed with the gear 25 fixed upon the feed rods 26. These feed rods extend on both sides approximately the full length of the machine and are guided by the brackets 27 fixed to the runways 28. These runways are supported by pillars resting upon the foundation 21.

The carrier 9 rests lightly upon the bed of the press A and is slidably mounted upon the rods 26 by the legs 29 engaging the rods. The collars 30 are fixed upon the feed rods between the legs 29. The rotation of the gear 16 acting through the pin and slot engagement with the sector 19 causes the rack to move forward. The interval between the collars 30 and their abutment with the contiguous leg 29 permits a dwell interval before the carriage starts forward. This dwell allows the pin 31 fixed upon the drive shaft to engage the trip 33 pivoted to the clutch rod 32 throwing the clutch mechanism 34 of the press into engagement with the clutch jaw on the fly wheel 35 that is belted to the constantly rotating line shaft 36. The engagement of this clutch mechanism 34 causes an action of the press downward forcing the notching dies through the body of the strips 5 forming notches on the opposite edges of both strips. A downward action of the dies carries the latch 37 pivoted on the cross bar 38 downward into engagement with the pin 39 fixed on the carrier 9. The return of the breast beam of the press leaves the punches engaged in the edges of the metal strips. The dwell interval having now passed, the collars 30 engage the legs of the carrier and carry it forward the predetermined distance between the cross tie clips 40, in this instance 24 inches.

For convenience of description, presume that the machine has been adjusted to form a studding composed of two parallel strips with cross tie clips fixed at 24 inch centers, the first tie being set three inches from the front end and the last one three inches from the rear end. At the limit of the forward movement of the carrier, the pin 41 mounted on the runway 28 forces the dog 37 out of engagement with the pin 39 which permits the compressed springs 42 under the bar 38 to withdraw the punches from engagement with the strips 5. The continued rotation of the gear 16 restores the sector and the carrier actuated thereby to the normal position with the notching dies beneath the breast beam 43 of the notching press A. The action thus described has carried the strips forward 24 inches and reset the notching dies for the succeeding set of notches. The clutch mechanism 12 being still in engagement, the operation is repeated, the

notching dies descending, locking, moving forward, unlocking and moving backward in the manner described, which forces the strips forward 48 inches, carrying the end beneath the first set of cutting dies 44 which are adjusted at "3" on the scale 45 to trim the ends of the strips three inches from the center of the first set of notches. 70

The operation of the cutting press B is synchronized with the operation of the notching press through the synchronizing gear set actuated by the main drive shaft 13 in the manner hereinafter more specifically described. The number of actions of the cutting press are determined by the 80 number of cross tied clips to be fixed in the completed length of studding.

The notching press continues to operate in the manner described until the notched strip is forced forward beneath the flanging or channeling dies 46 and 47 of the channeling press C. The clutch mechanism of this press C is operated by a trip mechanism actuated by the driving shaft in the manner described. It is the function of the press C 90 to flange up the edges of the strips at right angles changing the notches 51 from the horizontal to the vertical plane. 85

The strips are forced beneath the channeling dies which continue to operate, converting the strips into channels as they pass through the press C. Passing from the press C, the first notch formed in the strip receives a cross tie from the tie placing mechanism hereinafter described in detail. 95 This tie clip is engaged by the pawl 48 pivoted to the bracket 49 fixed on the feed rod 26. The notch dies and the pawl 48 both being mounted on the feed rod 26, act in unison at all times. When the last predetermined notch has passed into the cutting off press B, the strip is severed by the cutting die 50 three inches from the last notch, the die being set according to the scale 45. The reciprocation of the feed rods 26 actuating the pawl 48 continues to feed the channeled strips forward at regular intervals. 100 110

Between the channeling press C and the clenching press D, the cross tie feed mechanism E is introduced. It is the function of this mechanism to drop the angular notched cross tie clips 40 into the notches 51 formed in the strips that are kept in perfect register throughout their travel by the peculiar manner of feeding them forward by means of 120 the notching dies.

The tie clip placing mechanism consists of the chute or hopper 52 in which the clips are placed, nested together with their apexes up. The lower edge of one side of the hopper is turned in to form the flange 53 upon which one edge of the nethermost clip rests. The opposite edge of this clip is engaged by the escapement pawl pivoted at 54. The head of this escapement pawl is provided 125 130

with the notch 55 adapted to engage and support the edge of the nethermost clip until the pendulum of the pawl is engaged by the cam 56 fixed upon the feed rod 26. The swing of the pendulum swings the notch 55 downward permitting the nethermost clip to drop into the notch 51 in the studding of the strip timed to meet it by the placing of the cam 56. The edge of the succeeding clip

10 rests upon the head of the pawl until the lower clip is dropped and the notch 55 immediately returned to normal position by the action of the counter-weight 58. The pendulum is provided with the hinged strike plate 59 adapted to clear the cam 56 without tripping the pawl. It is obvious that other ways of placing the clips may be used.

After the cross ties drop into the notches as the channels pass beneath the feeding mechanism E, they are carried forward and clenched in positive engagement with the notches by the down stroke of the clenching die 98 operated by the press D. The clutch mechanism of the press D is actuated by a trip mechanism similar to that of the presses A, B and C, and is timed to operate during the dwell before described in connection with the operation of the notching press. Passing from the press D, the inserted tie 25 clips are successively engaged by the pawl 51 pivoted to the bracket 52 that is fixed on the feed rod 26. This latter pawl acting in unison with the pawl 46 and the primary feeding mechanism engages each successive 30 tie clip and acts as an ejector by engaging the last clip in the completed studding that is forced from the machine thereby.

The starting lever 11 is pivoted at 60 to the base of the pillar of the runway and 40 linked to the clutch 12 of the synchronizing mechanism. The lever is locked in position by the pivoted latch 61. This latch is tripped out of engagement with the lever 11 by the pin 62 fixed in the slide bar 63 tripped 45 by the swing lever 64. This lever is provided with a weight 65 on one side of its fulcrum, the opposite end being linked to the pin 66. The lever 64 and the pin 66 are duplicated for each runway of the machine, 50 whereby the failure of any strip would permit the pin controlled by that strip to rise, causing the lever attached thereto to drive against head 67 of the slide bar 63 extended across the machine in the path of the levers. 55 The release of the latch allows the spring 68 to throw the lever to the stop position releasing the clutch.

The electric welding mechanism consisting of the electrode α below the strip and 60 the electrode γ above the strip is provided for electrowelding the strip when occasion requires. Oxy-acetylene or other welding means may be substituted for the electric if desired.

65 Specific descriptions of the presses A, B,

C and D, and their clutch mechanisms, will be omitted as not germane to this invention. The conventional types of these machines are available in the practice of this invention, the particular functioning residing 70 within the dies operated by these presses, and the synchronizing mechanism coördinating the several machines into a working combination.

The presses are all actuated by the line 75 shaft 36 which is constant running, the fly wheels of the press running idle until the clutch is engaged therewith.

Various manners of operating the clutch mechanisms from the actuating shaft 13 are 80 also possible. That shown in connection with A, B, C and D consists of pins 31 fixed upon the actuating shaft and thrown into contact with the clutch setting mechanism 33 by the rotation of the shaft 13.

The synchronizing mechanism of the cutting press B is actuated by the eccentric 70 fixed upon the shaft 13 and engaged by the eccentric band 71 having the connecting arm 72 pivoted at 73 to the slide bar 74 guided 90 in the blocks 75 fixed upon the base 21 of the machine. The spring pawl 76 is pivoted at 77 on the slide bar and held in normal position by the spring 78. The head of the pawl engages the pins 79 extending from the 95 face of the disk 80 pivoted at 81 to the bracket 82 fixed to the base 21 of the machine.

The operation of the eccentric causes reciprocation of the slide bar, causing the 100 pawl 76 to engage the pins and rotate the disk 80; the pawl pulling forward on the pins on the forward movement and springing down and passing under on the reverse movement in an obvious manner. The detent roller 83 journaled in the spring bracket 84 fixed to the base 85 drops between the pins on the disk to prevent reverse motion. The opposite side of the disk is provided with one or more pins 86 adapted to engage 110 the trip 33 of the clutch mechanism throwing it into operation, causing the press to perform its function.

The number of pins in the disk corresponds to the number of cross die clips or 115 notches formed in the studding, this number being determined, of course, by the height of the ceiling, or other architectural specifications of the studding, it being the purpose to operate the cutting off press once 120 for each section of studding produced. There are two cutting off dies so as to simultaneously sever the strips for the terminal end of the first section of studding and the front end of the succeeding section of studding. These distances are fixed by the scale 125 45 as described.

The disks 80 are easily substituted when changes in the specifications of the studding call for more or fewer clips. A set of en- 130

meshed timing gears may be substituted for the construction just described. The former is preferred because of its ready adjustment and its cheapness in construction and operation, the character of the machine being considered.

The clutch mechanisms of the presses A, B, C and D previously described in general terms are constructed substantially as follows: The pins 31 are fixed in an adjustably fixed sleeve 88 on the drive shaft 13. The rotation of this shaft brings these pins into contact with the trip 33 connected to the rod 32, which throws the yoke 89 controlling the clutch collar 34, splined on the crank shaft of the press, into engagement with the free running fly wheel 35, the clutch jaw causing the latter to carry the press through one action down and return. The action of each press modifies the product in accordance with the forming dies operated by that particular press in action. The action of the various presses is timed by the set position of the pins 31 which coördinate or synchronize the actions of the combined presses.

As illustrated, the cutting off press B operates once to every twelve actions of the punching and feeding press A. Both are driven by the same shaft 13. A is tripped by the pin 86 once every revolution of the shaft, while B is tripped every 12 revolutions as determined by the number of pins in the disk 80. Thus, every revolution of the disk one complete "six tie" studding is formed.

The action of the cutting dies removes a length from the strips between two clips leaving a gap. The following end must be guided on the horizontal plane in passing between the cutting off dies as a gap is necessary in the runways 28. This gap is bridged over by the rods 92 suspended by the brackets 93 attached to the cutting die holders at 94. These rods align with the runways when the dies are in normal position and guide the strips across the gap necessitated by the cutting off dies. The rods 92 are carried downward by the stroke of the cutting dies, the severed pieces of strip dropping out of the machine. These odd lengths of strip are converted into tie clips to minimize waste of material. Various lengths of rods 92 are necessary to meet the demands of the specifications of the studding. Sections of the runways 28 are inserted on each outer side of the cutting off dies to complete the runways across the press B.

The moving of the pin 17 toward the center of the gear 16 by rotating the running screw 95 engaged therewith, the stroke of the sector 19 is shortened, consequently the movement of the feed rods 26 is shortened and the distance between the notches shortened, or vice versa. The pin 41 is also ad-

justed to release the dies at the proper time. This readjustment to meet changes in the distance between notches requires consistent adjustment of the cutting dies in press B, the length of the scale 45 sufficing for architectural standards in studding. The channeling dies 46 and 47 also are long enough to operate properly irrespective of the distance between notches. But the clenching press D must be adjusted to correspond with the exact advance of the feed rods 26. With this adjustment in view, the press D is mounted upon the horizontal bars 96 attached by the blocks 97 to the foundation 21. Loosening the clamps 97 permits the press to be adjusted longitudinally to match the feed of the notching dies. The brackets 49 and 52 are slideable on the feed rods for the purposes of accommodation in adjustments.

The down stroke of the press D forces the die 98 against the apex of the angular tie clip 40 forcing it flat, the notches 99 in the plate engaging the upstanding flanges of the channel within the notched edges 51 thereof, rigidly attaching the parallel channels together at each notched interval. More than two channels can thus be tied together by duplicating the capacity of the machine, and lengthening the tie plate. Thus assembled and coördinated, a working combination between the various elements of the machine is attained. It is obvious that one or more elements might be omitted or added to the combination to meet variations in the product. Equivalent structural modifications and alterations in the machine to meet conditions within the spirit of this invention will suggest themselves to those skilled in the art.

Having thus described this invention, what is claimed and desired to be secured by Letters Patent is:

1. A studding machine comprising a notching press, a cutting off press, clutch mechanisms on both of said presses, a channeling press, a clip placing mechanism and a clip clenching press, in combination with a synchronizing mechanism geared to the said clutch mechanisms of said presses, and a reciprocating feed mechanism geared to said synchronizing mechanism, notching dies operated by said notching press adapted to be forced through and engage strips of studding material and move forward with the feed mechanism when so engaged, to disengage from said strips and return with said feed mechanism leaving said strip advanced, the actions of all of said elements being synchronized and coördinated with the action of said notching dies.

2. A studding machine comprising a holder for continuous reels of studding strip, runways for said strips, notching dies, means for forcing said dies through said

strips a reciprocating feed mechanism engaging said dies, means for disengaging said dies from said strip at the forward limit of the movement of said feed mechanism, a synchronizing mechanism coördinating the actions of said dies and the feeding mechanism at predetermined intervals, a cutting off mechanism for said strips controlled by said synchronizing mechanism, a channeling mechanism engaging said strips at intervals controlled by said synchronizing mechanism, a feed pawl fixed on the feeding mechanism and engaging the notches formed by the notching dies, a tie placing mechanism controlled by the feed mechanism, a clenching die acting on said ties and the said strips at intervals determined by the synchronizing mechanism, and an ejecting pawl fixed on the feeding mechanism and engaging the successive notches formed by the notching dies.

3. A studding machine comprising a runway, a notching means, a channeling means and a tie clenching means interposed in said runway, means for advancing the material being operated on from one means to the other, a driving means, and means for synchronizing the actions of the above recited means.

30 4. A studding machine comprising a runway, a notching means, a cutting off means, a channeling means; and a tie clenching means interposed in said runway, means associated with the notching means for advancing the material being operated on from one means to the other, a driving means, and means for synchronizing the actions of the above recited means.

5. A studding machine comprising a runway, a notching means, a cutting off means, a channeling means and a tie clenching means interposed in said runway, a tie-placing means adjacent to said runway, means associated with the notching means for advancing the material being operated on from one means to the other, a driving means, and means for synchronizing the actions of the above recited means.

6. A studding machine comprising a runway, means for notching a metal strip arranged adjacent said runway, means for clenching a tie to said notched strip, a strip feeding means coöperating with said runway and means for driving said means.

55 7. In a studding machine, a runway, a notching means adapted to engage a strip on said runway and means for moving said notching means in the direction of the length of the runway while said notching means is engaged with said strip.

8. A studding machine comprising a notching press, notching dies operated by said press, a carrier for said dies having legs slidably mounted upon reciprocating rods, a collar fixed upon said rods between

the legs of the carrier, the collar being narrower than the space between said legs, and a rack bar fixed on said rods and enmeshed with a driving pinion geared to a reversing drive mechanism.

9. In a studding machine a feed mechanism comprising a set of notching dies adapted to lock into the material to be fed, a carrier for said dies slidably engaging feed rods with toothed engagement with a driving gear actuated by a pivoted sector having a slot and pin engagement, with a driving gear, and means for disengaging at the proper time said dies from the material to be fed.

10. In a studding machine a feed mechanism comprising a driving shaft, a bevel pinion fixed upon a driving shaft, a bevel gear enmeshed with the pinion, a pin adjustably fixed in said gear, a pivoted sector having a slot engaging said pin, a rack segment fixed on said sector enmeshed with a spur gear enmeshed with a rack on the feed rod, a collar fixed upon said rod, a carriage slideable on said rod engaging said collar, a press and dies mounted upon said carriage and operated by a press.

11. In a studding machine a runway, a set of notching dies adapted to punch through and carry forward studding strips, release said strips and move back with the feed mechanism and repeat the operation with said strips, cutting off dies, channeling dies, tie placing and clenching mechanisms interposed in the said runway in the path of the said strips, and a synchronizing mechanism coördinating the actions of said feed mechanism and the notching dies.

12. In a studding machine a runway for studding strips, a feeding mechanism comprising notching dies attached to the feeding mechanism and adapted to punch through and advance a plurality of studding strips in positive register, a plurality of cutting off dies in the path of said strips, adapted to be set independent distances from said notching dies, and a synchronizing mechanism interposed between said punching and cutting off dies.

13. In a studding machine a punching and feeding mechanism for studding strips operated by a synchronizing mechanism, a cutting off mechanism, a coördinating mechanism for the said cutting off mechanism consisting of an eccentric fixed upon the drive shaft of the synchronizing mechanism, and linked to a reciprocating slide bar, a spring pawl pivoted on said slide bar, a disk journaled adjacent to said slide bar and having pins interposed in the path of said pawl, a projection on said disk, a clutch trip on said cutting off mechanism interposed in the path of said projection on the disk.

14. In a studding machine having a run-

way, a reel holder for the studding strip, a set of straightening rolls coöperating with said runway for said strip, and a stop mechanism controlling the feed mechanism consisting of a pin passing through said runway between said straightening rolls and normally held inoperative by said strips.

15. In a studding machine, stock notching dies comprising die plates and punches, a latch attached to said punches adapted to engage and hold said die plates at the end of the downstroke of the punches, means for moving said dies transversely a predetermined distance and means arranged in 15 the path of said latch for releasing the latch at the end of its transverse movement.

16. In a studding machine, a runway for the studding stock, a press arranged in operative relation with said runway, cutting dies mounted in said press, means for adjusting said dies independently and trans-

versely and a stock feeding mechanism comprising notching dies arranged in a fixed relation with said press and adapted to feed the stock in a step by step movement. 25

17. In a studding machine, a runway for studding strips, a stop mechanism comprising pins projecting through the said runways for the studding strips and normally held in operation by said strips, a starting lever linked to the main clutch of said synchronizing mechanism, and a latch for said starting lever, and a weighted lever linked to said pins and said latch. 30

In testimony whereof, I have hereunto set 35 my hand at the city and county of San Francisco, this 17th day of October, 1912.

EUGENE WIET.

In presence of—

BALDWIN VALE,
FRED'K W. SPENCER.
